Primary Examiner — Janice Hallmark*Assistant Examiner* — Harold E Blackwell, II(74) *Attorney, Agent, or Firm* — Taft Stettinius & Hollister LLP(57) **CLAIM**

The ornamental design for trim, as shown and described.

DESCRIPTION

FIG. 1 is a front, top, right side perspective view of trim showing our new design;

FIG. 2 is a front elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The broken lines in the drawing figures form no part of the claimed design.

1 Claim, 3 Drawing Sheets(56)
